UNITED STATES PATENT OFFICE.

WILLIAM KIRN, OF NEW CAMBRIA, KANSAS

GATE AND BARN-DOOR LATCH.

1,120,943.

Specification of Letters Patent. Patented Dec. 15, 1914.

Application filed April 6, 1914. Serial No. 829,795.

To all whom it may concern:

Be it known that I, WILLIAM KIRN, a citizen of the United States, residing at New Cambria, in the county of Saline and State of Kansas, have invented certain new and useful Improvements in Gate and Barn-Door Latches, of which the following is a specification.

My invention is a latch of rugged construction such as is required in a gate latch, or a barn-door latch, or in other places where it is subject to hard use, exposure, and abuse.

The object of my invention is to improve generally upon this type of latches; to simplify and at the same time strengthen the construction; to reduce the necessary number of parts; to avoid the use of separate spring, using the handle as a spring; to make the latch readily adjustable to any thickness of door, gate, or other member to which it is to be applied, and to simplify the adjusting means; to make the latch so that it can be used on ordinary swinging doors or gates, and also on single sliding doors, and on double sliding doors; to provide a simple and efficient inside lock for locking the latch against both opening and closing; and to provide the parts, improvements, and combinations hereinafter set forth.

Figure 1 is a horizontal section of an ordinary side-swing door and of the adjacent door jamb, with a plan view of a latch and keeper secured to those respective parts and made in accordance with the principles of my invention, the two face plates being shown in section. Fig. 2 is a front or outside view of the same, without the door and jamb. Fig. 3 is a view of the latch from the opposite side, or inside. Figs. 4 and 5 show the face plates. Fig. 6 shows the stop and guide with a section of the latch lever, on line 6' in Fig. 2. Fig. 7 is a face view of the keeper; and Fig. 8 is a sectional view of the same on plane indicated by the line 8' in Fig. 7. Fig. 9 shows the method of applying the same parts to double sliding doors. Fig. 10 shows the method of applying the same latch to a single slide door, with another form of keeper, the keeper being shown in section on plane indicated by the line 10' in Fig. 12. Fig. 11 is another view of the parts shown in Fig. 10. Fig. 12 shows the keeper.

Similar reference characters indicate similar parts throughout the several views.

13 represents a side-swing door, and 44 the adjacent jamb. 14 is the pin or pivot spindle extending through the door; the same being turned at substantially right angles and formed with a loop 15, and then returns substantially parallel in the same general right angular direction, as indicated at 16, the extreme end being turned in close to the spindle portion, as shown at 17.

18 is the outside face plate formed with the two holes 19 for the reception of the spindle portion 14 and the inturned end 17, 73 the plate being secured to the door by means of suitable screws 20. One side of the spindle is flattened, as shown at 21, and the spindle extends through a correspondingly shaped hole in the central or hub portion 22 75 of the latch lever comprising a handle portion 23 and a locking arm 24, whose end is formed with the successively right-angular portions 25, 26, and 27, as shown in the drawings. The central or hub portion extends, as shown at 28, as a boss, into a hole 30 in the inside face plate 29 secured in place by means of suitable screws 31. The latch lever is firmly held to the spindle by means of a set-screw 32, which prevents 85 movement of the lever lengthwise of the spindle, thus holding the parts in proper relation.

33 is a guide and stop, to limit the oscillating movement of the latch lever. 90

It will be noted that the outside face plate is so fastened that the two holes 19 are slightly offset on opposite sides of the horizontal center line of the handle; this being for the purpose of tending to force the 95 handle upwardly and the locking arm of the latch lever downwardly against the guide. Also, the latch is operated by moving the handle downwardly and thus raising the locking arm, the downward movement of the handle being against the tension of the resiliency of the parts 15 and 16, which immediately restores the latch to normal position on being released. Obviously, by shifting the face plate and the 100 guide stop, the latch may be made to work by lifting the handle, and may be applied to either right or left side of the door and respond either to a downward or an upward movement of the handle. It will also 110

be noted that the latch may be easily adjusted to any thickness of door within the limit of the length of the spindle. The face plates hold the spindle always in proper 5 pivotal position.

The keeper 34 is formed with vertical slots 35 through which the screws 36 extend to secure it to the jamb, also with a tongue 37 that is tapered, as shown at 39 and also 10 bent inwardly at its end 37'. The tongue is also formed with shoulders or notches 38.

41 is a rod mounted in slots 42 and having ends 40 turned at right angles and embracing the top and bottom sides of the keeper. For a side-swing door, the keeper is fastened to the jamb as shown in Figs. 1 and 2. When the door is closed, the latch lever rides up on the tapered tongue against the tension of the spring handle and drops 20 in the notch 38. By moving the handle downwardly, the latch lever is released and the door may be opened. By turning the arms of the rod 41, 40 to the position shown by the dotted outline 43, the latch lever will 25 be locked in place so that it cannot be opened by operation of the handle. Also by so shifting the rod when the latch is out, the latch will be prevented from catching in the keeper. This special form of keeper 30 may be used for either left or right swing door; also it may be used with either an upward or a downward movement of the latch handle.

When used on double sliding doors (see 35 Fig. 9) the keeper may be attached to one of the doors as shown in Fig. 3, the doors being represented at 50 and 51, the operation being substantially the same, except that the end portion 27 engages the tongue and 40 notch. For a single sliding door, the latch may be adjusted for an upward handle movement, for use in connection with a keeper comprising a plate 54 with vertical 45 slots 55, and a rib 57 with a notch or shoulder 58.

52 is the single sliding door. See Figs. 10, 11, and 12.

The object of having the vertical slots in the keeper, is to adjust the keeper with the

sagging of the door without the necessity of new screw-holes.

Keeper plate 54 is secured to the jams by means of screws 56.

The latch may be used on barn-doors, gates, and elsewhere. On account of its 55 rugged construction it is capable of hard use. It is strong, durable, simple, and efficient, and as well has a wide range of use and of adjustment.

Having thus described my invention, 60 what I claim as new and desire to secure by Letters Patent is:

1. The combination of an outside face plate having two holes adjacent to each other, an inside face plate, a spindle extending through one of the holes in the outside face plate and also through said inside face plate, said spindle being formed with an exterior right-angularly bent portion to form an operating handle and returning to 70 and engaging in said other hole, and a latch lever adjustably and non-rotatably secured to the spindle and pivoted in the inside face plate.

2. The combination of an outside face 75 plate, an inside face plate, a spindle extending through said plates and having its exterior portion bent substantially at right angles to form an operating handle and also doubled back upon itself to a free end, said 80 spindle and said free end being pivoted in the outside face plate, and a latch lever mounted on the spindle and pivoted in the inner face plate.

3. The combination of a face plate, a 85 spindle extending therethrough and bent at substantially a right angle to form a handle and also doubled back upon itself to a free end, said spindle and said free end being pivoted in the face plate, and a latch lever 90 mounted on the spindle.

In testimony whereof I have affixed my signature in presence of two witnesses.

WILLIAM KIRN.
